FRED A. NOETZLI, OF LOS ANGELES, CALIFORNIA

DAM CONSTRUCTION

Application filed November 14, 1928, Serial No. 319,205. Renewed March 20, 1931.

This invention relates to improvements in dam constructions.

An object of the invention is to provide a dam of novel construction and which is highly advantageous and which is a combination of a dam of arch construction and dams of gravity section construction.

Another object of the invention is to provide a dam having its central portion of arch construction and its sides or wings of gravity section construction and having buttresses which cooperate with the wings or sides of the dam in sustaining the thrust of the arched portion of the dam. The combination is highly advantageous in that the buttresses do not alone sustain the thrust of the arch but instead the portions of the dam which are of gravity section assist in weighting down the ends of the arch and in sustaining the thrust. In large concrete structures many stresses are set up in the structure for various reasons, such as those due to temperature changes and shrinkage of the concrete. Unless these stresses are taken care of at intervals along the concrete structure, cracks develop, which are irregular and which weaken the structure. This feature has been recognized in my co-pending application, Serial No. 221,197, filed September 17, 1927, over which the construction disclosed in this application may be considered as an improvement.

It is another object of this invention to provide a construction for dams of the gravity section type which employ long expanses of concrete wherein joints are established at intervals to permit shrinkage and temperature changes without weakening the dam.

Other objects of the invention are to provide novel and advantageous joint constructions and drainage systems.

With the foregoing and other objects in view which will be made manifest in the following detailed description and specifically pointed out in the appended claims, reference is had to the accompanying drawings for an illustrative embodiment of the invention, wherein:

Fig. 1 is a schematic top plan view of the dam embodying the invention.

Fig. 2 is a vertical section through one of

the gravity type wings of the dam shown in Fig. 1 and may be considered as having been taken upon the line 2—2 upon Fig. 1.

Fig. 3 is a partial view in horizontal section through the gravity wing shown in Fig. 2 and may be considered as having been taken upon the line 3—3 upon Fig. 2.

Referring to the accompanying drawings wherein similar reference characters designate similar parts throughout the dam consists of an arched central portion 10 which is shown as being a single arch. It is to be understood, however, that if desired a multiple arch form of construction may be employed for the central portion. At the ends of the arch there are formed buttresses 11 arranged on the downstream side or on the back of the dam which assist in sustaining the thrust of the arched central portion 10. Extending laterally from the ends of the arched central portion are wings or sides 12. These wings or sides are of the gravity type construction, that is, of the construction wherein the dam is kept from overturning by its own weight. Fig. 2 illustrates how such gravity type dam or wings appear in section with the rear side of the wall sloping downwardly and rearwardly so that the bottom of the wall is much thicker than the top. The buttresses 11 and their adjacent wings or sides 12 form an acute angle so that the thrust of the arched central portion 10 is partly sustained by the gravity type wings 12 and partly sustained by the buttresses 11. Neither the buttresses or the wings alone carry the thrust of the arched central portion but the stresses developed by the thrust are divided between these parts. The forward sides or forward faces of the gravity type wings 12 are exposed to the water pressure to which the central arched portion 10 is exposed and by virtue of the fact that these wings are of the gravity type construction they not only assist the buttresses in sustaining the thrust but serve also to a large extent in anchoring or weighting the ends of the arch. In this manner a novel and advantageous form of construction is provided for the improved dam.

As previously explained, large concrete structures are apt to crack, due to shrinkage

and temperature changes, unless provision is made for these changes. A novel construction for gravity type dams which takes care of the shrinkage and temperature changes is disclosed in Figs. 2 and 3. This construction, while it is shown as being employed only on the gravity wings 12 of the dam could be employed equally well throughout a dam which is entirely of gravity section, extending completely across the canyon. To provide for the temperature and shrinkage changes a series of transverse joints 16 are formed in the body of the gravity type dam. They are arranged at suitable intervals, usually approximately fifty feet apart. Longitudinal joints 17 and 18 are also formed in the body of the dam which extend from the bottom of the dam upwardly and forwardly to a point near its forward face. The longitudinal joints 17 and 18 are also preferably in the neighborhood of fifty feet apart. While these joints are preferably inclined, the transverse joints 16 are usually vertical. As clearly shown upon Fig. 3 the longitudinal joints 17 are staggered with respect to the longitudinal joints 18, forming sections or columns which are indicated on Fig. 3 respectively by the reference characters 19^a, 19^b, 19^c, 19^d, 19^e, and 19^f, this view illustrating a typical section through the wing. Beads or keys 20 are formed on one side of each of the columns or sections 19 and complementary grooves 21 are formed on the other side of each of the sections or columns 19 to receive the keys. These keys and grooves are formed on the transverse joints 16. They are so arranged that the various sections or columns 19 will be effectively tied together, thus if the section or column 19^d should be forced moved rearwardly or tend to settle in this direction the beads or keys 20 fitting in their grooves 21 will prevent this movement unless sections 19^b and 19^f moved with it. Sections 19^b and 19^f have bead and groove connections with the section or column 19^c so that the sections or columns 19^b and 19^f cannot move rearwardly without also moving section or column 19^c. Section or column 19^c cannot move without also moving sections or columns 19^a and 19^e and in this way all of the sections or columns are effectively tied together against great movement relatively to each other.

The transverse joints 16 and the longitudinal joints 17 and 18 may be established in any suitable manner so that there will be weakened bonds arranged along predetermined planes between the various sections or columns 19. These joints can be established such as by placing paper between the columns while they are being poured or if desired various sections or columns can first be poured and after they have set the other columns can be poured. The joints can also be established by painting the faces of the sections

or columns with asphaltum which is preferred, the object in all instances being to have definite joints along predetermined planes which have weakened bonds. These joints permit slight relative movement between the various sections or columns due to shrinkage and temperature changes so that no cracks will be formed except in the joints. The keys 20 in the grooves 21 permit the slight relative movement due to shrinkage or temperature changes but do not permit a material relative movement. The sections or columns may be connected together across the joints by sheet metal water stops 22 as being somewhat S shaped in section and extending across the joints and being embedded in the sections or columns 19. These sheet metal water stops permit the slight relative movement that may be necessary between the sections or columns due to temperature or shrinkage changes.

If desired, one or more or even all of the longitudinal joints 17 and 18 may be stepped or provided with keys as indicated upon the joint 23 upon Fig. 2. These keys or steps serve to tie the various columns or section 19 together against any material settling relatively to each other. At the tops of the longitudinal joints there may be formed holes 24. These holes serve the following function: If the joints should tend to open, due to shrinkage or temperature changes or settling of the columns the joints will not open beyond these holes or openings as the stresses will be distributed over the interior surface of the holes or openings, consequently widening or opening of the joints will not extend beyond the holes or openings 24 and therefore will not form cracks extending through the dam to its forward face. The function of the holes or openings 24 in thus preventing the formation of cracks which would be the continuations of the joints may be assisted by reinforcing bars 25.

At suitable intervals throughout the dam there are formed drain ports 26 which communicate with the joints 16, 17 and 18 and provide for the removal of any water seeping through the dam and trickling downward through the joints. The drain ports indicated at 26 terminate on the rear side of the dam and where the dam is of considerable thickness additional drain ports 27 may be formed therein for removing water from between forward joints and conveying it to a tunnel 28.

From the above described construction it will be appreciated that a novel form of dam is provided which is highly advantageous in its general form and also in the details of construction so as to render a very strong and sturdy dam structure. By having the gravity type dam divided into sections or columns 19 shrinkage and temperature changes and slight settling is effectively taken care of without danger of forming disastrous cracks.

in the structure. Furthermore, each column is arranged in a direction of the principal stresses in the dam when fully loaded and functions in a manner similar to an ordinary column in sustaining its proportion of the load, consequently unusual or unnatural stresses developed in one column or section 19 will not affect other columns.

Various changes may be made in the details 10 of construction without departing from the spirit or scope of the invention as defined by the appended claims.

I claim:

1. In a concrete dam, a wall of gravity 15 section supporting water pressure by virtue of its weight, there being an inclined joint in the interior of said wall extending from a point near its base upwardly and forwardly to a point near the upstream face of

20 said wall parallel to the direction of certain principal stresses when said wall is subjected to the full pressure of water in the reservoir.

25 2. In a concrete dam, a wall of gravity section supporting water pressure by virtue of its weight, there being an upwardly and forwardly inclined joint in the interior of said wall, said joint being arranged approximately parallel to the lines of zero shear in said wall when the dam is loaded, and means 30 for preventing an extension of the joint beyond its upper end.

3. In a concrete dam, a wall of gravity section supporting water pressure by virtue of its weight, said wall comprising portions 35 separated by substantially vertical contraction joints, there being one or more upwardly and forwardly inclined joints in the interior of one or more of said portions, and means providing key and groove connections between the portions thus defined by said joints for tying the portions together against material relative movements between each other.

4. In a concrete dam, a wall of gravity 45 section supporting water pressure by virtue of its weight, there being an upwardly and forwardly inclined joint in the interior of said wall, said joint being arranged approximately parallel to the direction of certain principal stresses when the dam is loaded and 50 being irregular so as to form an interlock across the joint so as to prevent material relative displacement between the portions of the dam on opposite sides of the joint.

5. In a concrete dam, a wall of gravity 55 section supporting water pressure by virtue of its weight, there being transverse joints formed through the wall, and longitudinal joints formed in the wall which are forwardly and upwardly inclined.

6. In a concrete dam, a wall of gravity 60 section supporting water pressure by virtue of its weight, there being transverse joints formed through the wall, and longitudinal joints formed in the wall which are forwardly and upwardly inclined, certain of the longi-

tudinal joints being staggered with respect to others.

7. In a concrete dam, a wall of gravity section supporting water pressure by virtue of its weight, there being transverse joints 70 formed through the wall, and longitudinal joints formed in the wall which are forwardly and upwardly inclined, some of the longitudinal joints being staggered with respect to others, there being key and groove connections formed between the portions of the wall defined by said joints so as to effectively tie the portions together against material relative displacement.

8. A gravity type dam divided into sections by longitudinal and transverse upwardly extending joints, the joints being roughly fifty feet apart so as to provide for shrinkage.

9. A gravity type dam divided into sections by longitudinal and transverse upwardly extending joints, the joints being roughly fifty feet apart so as to provide for shrinkage, at least some of the longitudinal joints being arranged in staggered relation on opposite sides of the transverse joint.

10. A gravity type dam divided into sections by longitudinal and transverse upwardly extending joints, the joints being roughly fifty feet apart so as to provide for shrinkage, at least some of the longitudinal joints being arranged in staggered relation, and means preventing relative lateral displacement between the sections on opposite sides of the transverse joints.

11. A gravity type dam divided into sections by longitudinal and transverse upwardly extending joints, the joints being roughly fifty feet apart so as to provide for shrinkage, the longitudinal joints being arranged in staggered relation, there being beads formed on transversely extending sides of the sections fitting in grooves in the transversely extending sides of adjacent sections.

12. A gravity type dam divided into sections by longitudinal and transverse upwardly extending joints, the joints being roughly fifty feet apart so as to provide for shrinkage, there being pairs of spaced water stops connecting the sections across the forward ends of the transverse joints.

13. The method of pouring a gravity type dam which consists of pouring transversely spaced upwardly extending sections of approximately fifty feet in width and breadth 120 which are roughly fifty feet apart in a transverse direction, allowing the sections to set and shrink, and then pouring the intervening sections after the initial shrinkage of the first sections has taken place providing longitudinal expansion joints between the first and intervening sections.

14. In a concrete dam resisting water pressure by virtue of its weight, a wall extending transversely to the direction of the dam,

there being an upwardly extending expansion joint across said wall, and key connections between the parts of the wall on opposite sides of the joint whereby shrinkage of the concrete may cause the expansion joint to open slightly without permitting said parts to settle materially relatively to each other.

15. In a concrete dam resisting water pressure by virtue of its weight the combination of at least two upwardly extending columns arranged one alongside the other in an upstream and downstream direction, an expansion joint between two of said columns, keys on one of said columns and complementary grooves in the adjoining column tending to prevent material settling of said columns relatively to each other.

16. A concrete dam resisting water pressure by virtue of its weight, said dam being divided into sections by intersecting transverse and longitudinal expansion joints, at least some of said longitudinal joints being arranged in staggered relation.

17. A concrete dam resisting water pressure by virtue of its weight, said dam being divided into sections by intersecting transverse and longitudinal expansion joints, at least some of said longitudinal joints being arranged in staggered relation with respect to each other, and drainage means for facilitating the removal of water from said longitudinal joints.

18. In a concrete dam, a wall of gravity section supporting water pressure by virtue of its weight, said wall being divided into sections by an upwardly and forwardly inclined expansion joint, said joint being arranged approximately parallel to the lines of zero shear when the dam is fully loaded and terminating short of the upstream face of the wall.

19. In a concrete dam, a wall of gravity section supporting water pressure by virtue of its weight, said wall being divided into sections by an upwardly and forwardly inclined expansion joint, said joint being arranged approximately parallel to the lines of zero shear when the dam is fully loaded and terminating short of the upstream face of the wall, and means preventing extension of the joint beyond its upper end.

20. In a concrete dam, a wall of gravity section supporting water pressure by virtue of its weight, said wall being divided into sections by upwardly extending transverse expansion joints, said sections being again divided into smaller sections by longitudinal expansion joints.

21. In a concrete dam, a wall of gravity section supporting water pressure by virtue of its weight, said wall being divided into sections by upwardly extending transverse expansion joints, said sections being again divided into smaller sections by longitudinal

expansion joints which are upwardly and forwardly inclined.

22. In a concrete dam, a wall of gravity section supporting water pressure by virtue of its weight, said wall being divided into sections by upwardly extending transverse expansion joints, said sections being again divided into small sections by longitudinal expansion joints, some of the longitudinal joints being staggered with respect to the others.

23. In a concrete dam, a wall of gravity section supporting water pressure by virtue of its weight, said wall being divided into sections by upwardly extending transverse expansion joints, said sections being again divided into smaller sections by longitudinal expansion joints, said sections having bead and groove connections across the joints to promote monolithic action.

24. In a concrete dam, a wall of gravity section supporting water pressure by virtue of its weight, said wall being divided into sections by upwardly extending transverse expansion joints, said sections being again divided into smaller sections by longitudinal expansion joints which are upwardly and forwardly inclined, the longitudinal joints terminating short of the upstream face of the wall and being staggered.

25. In a concrete dam, a wall of gravity section supporting water pressure by virtue of its weight, said wall being divided into sections by upwardly extending transverse expansion joints, said sections being again divided into smaller sections by longitudinal expansion joints which are upwardly and forwardly inclined, the longitudinal joints terminating short of the upstream face of the wall and being staggered, there being bead and groove connections connecting the sections across the joints.

26. The method of pouring a concrete dam divided into sections arranged one behind the other in a transverse direction which consists of pouring spaced sections, permitting said sections to set and shrink, and then pouring the intervening sections after the initial shrinkage of the first sections has taken place, producing expansion joints between the first sections and intervening sections.

27. The method of constructing a concrete dam by first building a certain upstream portion of the dam to an elevation lower than the final height of said dam, then building a downstream portion against the downstream face of said upstream portion, the area of contact between said upstream and said downstream portions being substantially parallel to the direction of first principal stresses when the dam is fully loaded.

28. The method of constructing a concrete dam as described by claim number 27, and further providing key and groove connec-

tions between said upstream and downstream portions of the dam.

29. A concrete dam supporting water pressure by virtue of its weight, said dam being divided into portions by upwardly extending transverse expansion joints, said portions being again divided into sections by upwardly extending longitudinal joints, and means interposed in said longitudinal joints 10 for promoting monolithic action of said portions.

In testimony whereof I have signed my name to this specification.
